MAILBOX WITH DOOR-ACTUATED SIGNAL

Filed April 14, 1947

UNITED STATES PATENT OFFICE

2,477,379

MAILBOX WITH DOOR-ACTUATED SIGNAL

William J. Korth, Cleveland, Ohio, assignor to
Pioneer Products Company, Cleveland, Ohio, a
partnership

Application April 14, 1947, Serial No. 741,183

3 Claims. (Cl. 232—35)

1

This invention relates to mailboxes and more particularly to mailboxes having associated signaling systems by which deposit of the mail or the calling of a visitor may be announced.

An object of my invention is to provide a mailbox of improved design which will give a distinctive signal to the members of the household when the mail is deposited. Another object is to provide a mailbox having an associated doorbell circuit, which in part provides means for signaling deposit of mail and otherwise operates as a conventional doorbell circuit, and which further may be selectively adjusted as desired to give yet another signal; for example illuminating a message when the occupants are not at home, or when under other circumstances such illumination should be desirable. Still another object is to provide a mailbox which is attractive in appearance, economical to manufacture and which is durable and strong and convenient to use. An additional object is to provide a mailbox in which mail inside the box cannot be removed through the mail slot without signaling to the household that the box has been opened.

Other objects and advantages will appear from the following description of my invention reference being made to the accompanying drawings in which: Figure 1 is a perspective view of a preferred form of my improved mailbox; Figure 2 is a longitudinal section as indicated by lines 2—2 of Figure 1 and on a somewhat larger scale; Figure 3 is a rear elevation of the upper portion of the mailbox with the cover plate removed; Figure 4 is a section of the upper portion of the mailbox taken along the lines 4—4 of Figure 3; Figure 5 is a wiring diagram showing the electric circuits associated with the mailbox; Figure 6 is a somewhat diagrammatic view of a modified form of the invention showing a form of mechanical means for operating the bell switch.

Referring now to the drawings, my invention comprises a mailbox 10 which in appearance generally takes conventional form but which has associated with it a doorbell circuit and other circuits to give appropriate signals in a manner to be described. Thus when the lid 11 of the mailbox is lifted in order that mail may be left within the box, a switch 12 is operated by the lid to ring a doorbell within the house. The box is also provided with a manual push button 13 by which a

2

visitor can announce himself in the usual manner. Lastly a light circuit controlled by the push button 13 and also by a selector switch 14 is provided so that for one position of the switch 14 a message can be illuminated when the push button 13 is manually depressed.

The box itself comprises a body 15 open at the back and at the bottom, a lid 11 hinged to the top of the body 15, a back panel 16 preferably taking the form of a flat metal sheet secured to the body, and lastly a bottom 17 which may be opened by being pulled forward to provide access to the interior of the box to remove letters and other mail.

The body portion 15 is preferably molded in one piece from opaque or translucent glass or plastic, although any other suitable material may be used. It has sides 18, a front panel 19 joining the side panels, and a top panel 20 integrally connected to the sides and front panel, and intersecting the latter at an angle of approximately 45° as shown. The upper rear ends of the sides terminate in upstanding lugs 21 and the top panel 20 extends rearwardly to a point just short of the lugs. As will be described later the sides 18 project downwardly beyond the front panel 20 forming extensions provided with interior transverse grooves 23 which extend the full width of the sides. The top panel has a slot 22 through which letters and other mail may be inserted and the dimensions of the box are such that once a full sized letter is inserted, it will lie a substantial distance below the slot making its withdrawal through the slot difficult.

The bottom of the mailbox is in the form of a slide which may be pulled forwardly, permitting access to the box and allowing the mail to be taken from the box, and comprises a sheet metal panel which slides in the horizontal grooves 23 located in the interior surfaces of the sides of the body 15 just below the lower edge of the front panel 19. The grooves 23 extend from the front to the rear of the box providing ways in which the panel rides and are large enough to prevent binding and ensure free sliding of the panel. The front end of the bottom panel is bent upwardly forming a right angle flange 24 upon which is mounted a lock 25 of any convenient type, the lower edge of the front panel 19 being provided with a notch 26 to provide room for the lock. The flange 24 limits the inward travel of the bottom

panel while its forward travel is limited by a pair of vertical upstanding tabs 27 struck from the bottom panel adjacent the rear corners. When the bottom is pulled out the tabs will strike the inner surface of the front panel 19 of the box and prevent the bottom from being fully withdrawn. The slide is unlocked and opened when it is desired to remove mail from the box.

While the body 15 forming the front and sides of the mailbox is of translucent glass the back panel 16 is made of stiff sheet metal, extending from the lower edges of the sides 18 vertically upward to a point substantially opposite the upper edge of the front panel at which point it is turned inwardly into the box extending inwardly and upwardly from that point at an angle of approximately 45° until it meets the top panel 20 just to the rear of the slot, thus forming a diagonal switch-supporting panel 30 as shown in Figure 1. The back 16 is secured to the glass body 15 by screws extending through the back and embedded in cement-filled recesses with which the side walls of the body are provided when it is molded.

The lid 11 is made of plastic and includes a main portion 31 which normally lies upon the top panel 20 covering the slot and protecting the contents of the box. It is indented as at 32 to form a rearwardly extending tongue 33 lying at an angle of approximately 45° with the main portion 31 to fit between the lugs 21, the lid being hinged for pivotal movement relative to the box upon pins 34 passing through the lugs and extending into the sides of the tongue.

When the lid is raised so that access may be had to the slot for the insertion of mail into the box, the tongue 33 swings downwardly closing the switch 12 to complete a doorbell circuit causing a doorbell to ring and thus give notice to the occupants of the house that mail has been delivered.

The switch 12 is mounted on the diagonal panel 30 in a position to be engaged by the tongue 33 as the lid is lifted and comprises two resilient arms 35 and 36 carrying contacts 37 and 38 respectively, the switch normally being in open position with the contacts spaced slightly apart.

The contact arms are of substantially equal length and have beaded or slightly rounded tips as shown and are so positioned in relation to the path of the tongue that when the lid is raised and the tongue swings down into the mailbox the tip of the arm 36 will be engaged and the arm carried along by the tongue for a short distance, the switch being closed for only a short interval before the arm 36 can slip free of the tongue and separate the contacts. Further movement of the tongue also engages the contact arm 35 and carries it away from closed position ensuring separation of the contacts; the arm 35 also being arranged so that it will slip free of the tongue after a momentary engagement. In like manner when the lid is dropped and the tongue returns contact arm 35 will be moved to the right as viewed in Figure 2 to close the switch momentarily before the tongue swings clear of the switch.

The result of raising the lid is to cause two sharp short rings of the doorbell, one when the lid is raised, the second when the lid is lowered. This signal is easily recognized and under most circumstances cannot be confused with the ordinary ringing of the doorbell by a caller. Moreover the arrangement ensures that the bell will not keep on ringing if the lid should remain

propelled in fully open position by the insertion of bulky mail.

Parallel to and utilizing a portion of the above described bell circuit is a second doorbell circuit by means of which a visitor may announce himself in the usual manner. Controlling this circuit is a push button 13 located on the front panel 19 and which, when pushed, will ring the same doorbell which responds to the opening of the lid.

This second circuit also includes a selector switch 14 which affords the choice of an alternate or additional signal upon operation of the push button. The selector switch 14 is mounted upon the diagonal support 30 adjacent the upper right side of the body as viewed in Figure 4 and has a knob 40 which extends through a slot 41 in side 18 so that access to the switch from outside the mailbox is convenient and easy. The switch 14 in the form illustrated enables selection of either a doorbell circuit or a light circuit or both. Thus when the residents of the house are at home the switch will be turned to the doorbell circuit position so that depressing the push button will ring the doorbell. On the other hand when the residents are away from home the switch can be turned to the light circuit position and then when the push button is depressed a light will come on directing attention of the caller to an illuminated message carried by the box on the inside of the translucent lid 11 so that light shining through the lid from a point within the box will silhouette the message. The message is particularly noticeable especially since it is located just above and close to the push button to which the eye of the caller is naturally addressed. The light is provided by a small bulb 43 mounted on a bracket 44 struck from the central portion of the diagonal support 30 and bent back to a vertical position as shown in Figures 2 and 3.

The switch 14, which enables selection of either signal or if desired both signals at once, as shown in Figure 4 consists of a pivotally-mounted arm 45 which is adapted to contact either or both of a pair of spaced contacts 46 and 47; contact 46 being included in the light circuit and contact 47 in the doorbell circuit. A knob 40 is secured to the end of the arm 45 and extends through the slot 41 to the outside of the box permitting the switch to be conveniently set. If the bell signal alone is desired the switch arm is moved to the right as viewed in Figure 4 to bear against the contact 47; if the light signal is desired the arm is moved to the left to engage contact 46. If both signals are desired the arm can be left in a middle position as shown in Figure 4 since it is of sufficient width to span the distance between both contacts.

In the figures of the drawing referred to so far the electrical connections and leads are omitted for convenience in illustration and description. The required electrical circuits are shown in Figure 5 in which like reference characters are used as for the previously described figures. The circuit established by raising the lid can be traced in the lower right-hand portion of Figure 5, the circuit for lighting the light can be traced in the left-hand portion of Figure 5, while the push button doorbell circuit is shown to be in parallel with the lid bell circuit on the right-hand side. The push button 13 is in parallel with the switch 12 and is in series with the doorbell when the arm 45 of switch 14 is in its right-hand position but the button is in series with the light 43 when the switch 14 is in its left-hand position. When the

arm 45 of switch 14 is in its middle position the button 13 will both ring the bell and light the lamp.

The respective switches, lamp socket and many of the connections can be mounted and assembled on the diagonal bracket 30 before the back 16 is secured to the body 15. All that remains, thereafter, is to make the electrical connections with the push button 13 in order to have the electrical assembly substantially complete. A cover plate 48 is then secured to the side walls as shown serving to conceal and protect the switches and other parts, the cover plate having openings through which suitable leads may pass to connect with a source of power and the doorbell both of which are most conveniently located within the house.

A modified form of my invention is illustrated in Figure 6 in which the push button 13 and switch 12 are connected by a mechanical linkage rather than by electrical connections enabling the other electrical apparatus to be entirely mounted and assembled on the diagonal bracket 30. As shown somewhat diagrammatically in Figure 6 the push button 13 is connected to a stiff but somewhat resilient wire 50 which in turn is connected to or bears against the contact arm of switch 12. The wire transmits mechanical movement of the push button to the switch so that depressing the button will result in closing the switch 12. A sleeve 51 passing through the diagonal support 30 supports and locates the wire in relation to the switch 12. Although for the sake of appearance I have shown the push button 13 to be centrally located in the front of the box it may be found desirable to position it adjacent to the left side of the box as viewed in Figure 6 so that a straight connecting piece, rather than an angled wire, may be utilized.

In this form of my invention the circuits may also be conveniently modified, in this instance the switch 12 being connected in series with the selector switch 14, and the doorbell and the light being connected in parallel with each other. Then, depending on the setting of the selector switch 14, closing of switch 12 by either raising the lid or pressing the button will ring the doorbell or light the bulb or both. However in this modification, the distinctive signal, i. e. the two sharp rings of the bell, is still retained.

From the foregoing description it will be seen that I have provided an improved mailbox construction including various signaling means in combination with it that provides an improved unit over prior known constructions.

I claim:

1. A mailbox construction comprising a generally flat back plate, a channel shaped member including a front face and side faces and secured by the edges of said side faces to said back plate, a light transmitting top plate across the top end of said channel portion to close the same, a mail slot in said top plate, a light transmitting member pivotally hinged to said side faces at the top thereof and adapted to cover said slot, a light carried by said back plate to project light up toward said top plate, a switch having a contact member mounted on said back plate and adapted to be actuated by said hinged member when said member is rocked about its pivot, a push button having a contact member mounted in said channel member, connections leading from said switch and

button to a source of current and a bell outside said box and a switch carried by said box selectively to connect said push button to said connections to establish alternate electric circuits either lighting said light or ringing said bell or both.

5 2. A mailbox construction comprising a generally flat back plate, with an upper and a lower end portion, said upper portion being bent diagonally upwardly from the plane of said back plate 10 to provide a panel lying at an angle of substantially forty-five degrees thereto, a channel shaped member including a front face and side faces and secured by the edges of said side faces to said back plate, a light transmitting top plate across the top end of said channel portion to close the same, a mail slot in said top plate, a light transmitting member pivotally hinged to said side faces at the top thereof and adapted to cover said slot, a light carried by said diagonally bent back plate portion to project light up toward said top plate, a switch having a contact member mounted on said back plate and adapted to be actuated by said hinged member when said member is rocked about its pivot, a push button having a contact member mounted in said channel member, connections leading from said switch and button to a source of current and a bell outside said box and a switch carried by said box selectively to connect said push button to said connections to establish alternate electric circuits either lighting said light or ringing said bell or both.

3. A mailbox construction comprising a generally flat back plate, a channel shaped member including a front face and side faces and secured by the edges of said side faces to said back plate, a light transmitting top plate across the top end of said channel portion to close the same, a mail slot in said top plate, a light transmitting member pivotally hinged to said side faces at the top thereof and adapted to cover said slot, a light carried by said back plate to project light up toward said top plate, a contact member mounted on said back plate and adapted to be actuated by said hinged member when said member is rocked about its pivot, a push button having a contact member mounted in said channel member, connections leading from said contact members to a source of current and a bell and a switch carried by said box selectively to connect said contact members to said connections to establish alternate electric circuits either lighting said light or ringing said bell or both when one of said contact members is actuated.
